STAPLING DEVICE

Alfonso F. Valdez, Houston, Tex.

Application May 24, 1954, Serial No. 431,667

1 Claim. (Cl. 1—101)

This invention relates to new and useful improvements in a stapling machine.

It is an object of the invention to provide a stapling machine for use in stapling small packages to a cardboard sheet.

In marketing spices and the like, which are packaged in small, transparent bags, it is customary to attach a prescribed number of packages to a cardboard display card for the merchant to hang on a rack and which packages the customers easily remove from the card. To accomplish this, the packages are usually stapled to the cardboard, and the method of stapling is usually a manual manipulation of a stapling machine, which requires placing the card and package at an angle in the machine and manipulating a foot pedal to fasten the staple. It is an object of this invention to provide a machine that will electrically operate the device and that will permit rapid fastening of the packages to the cardboard display card.

With the above and other objects in view, the invention has relation to certain novel features of operation and construction more particularly defined in the following specifications and illustrated in the accompanying drawings, wherein:

Figure 1 is a top plan view of the device.

Figure 2 is a front elevational view, and

Figure 3 is a diagrammatic sketch of the wiring.

Referring now more particularly to the drawings, the numeral 1 designates a conventional stapler mounted on

2

a suitable base as 2. A housing 3 encloses an electrically operated actuator arm 4, which is actuated by a solenoid as 5. A suitable insulating pad 6, such as sponge rubber, is mounted between the housing 3 and the base 2.

5 Mounted on the base 2 adjacent the forward end of the stapling device 1 is a contact switch 7. When a cardboard backing, as 8, is inserted between the jaws of the stapling device 1, and the package 9 to be stapled thereon is placed in the desired position on the cardboard backing, the cardboard backing it tilted, pressing on the switch 7, and completing a circuit through the solenoid 5, causing the actuating arm 4 to move downwardly, pressing the plunger 11 of the stapling device downwardly, and fixing a staple in the package and backing board. A suitable rubber bumper, as 12, may be mounted between the top of the plunger 11 and the end of the actuating arm 4, promoting silent operating of the device.

10 The construction above set out permits rapid and accurate assembly of a display card with the desired number of packages stapled thereto in a minimum of time and with a minimum of effort.

15 While the foregoing is considered a preferred form of the invention, it is by way of illustration only, the broad principle of the invention being defined by the appended claim.

20 What I claim is:

25 In a stapling device, a staple dispensing means having elongated jaws, an actuating device extending outwardly and rearwardly from said jaws and in operative connection with said staple dispensing means, an electrically operated solenoid in said actuating device, a pressure sensitive switch adjacent said jaws, means for opening and closing said switch upon tilting of a display card inserted between the said jaws.
